RECORDING AND REPRODUCTION OF
ELECTRICAL IMPULSESEdward W. Kellogg, Moorestown, N. J., assignor
to Radio Corporation of America, a corpora-
tion of Delaware

Application March 31, 1939, Serial No. 265,271

5 Claims. (Cl. 179—100.3)

This invention relates to the photographic recording and reproduction of electrical impulses such as those of audio frequency, and has for its principal object the provision of an improved apparatus and method of operation whereby different frequency components of said impulses are recorded in such different forms as are required to obviate the distortion ordinarily involved in recording all the impulse frequencies in the same 10 form.

It is known that the variable density type of photographic record is relatively less distorted in the high frequency range and that the variable area type of record has certain advantages in the 15 low frequency range. Thus, in the case of the variable area record, the limited resolving power of photographic film causes the valleys of the high frequency waves to be filled in or fogged, and the high frequency peaks to be underexposed. 20 Due to the loss of transmission in the valleys, the amplitude of the recorded waves is decreased and the high frequencies are attenuated. This reduction in average transmission results in extraneous sounds, the frequencies of which depend upon the 25 envelope of the recorded high frequency components. A low frequency variable area record, however, has the advantage that it is less distorted by the development or processing of the photographic film.

30 A further object of the invention is to provide an improved sound record, whereby the above types of distortion are avoided. To this end, the relatively high frequency components of the sound are recorded by the variable density method and the relatively low frequency components are recorded by the variable area method. More specifically, the lower frequencies are recorded in the form of a push-pull variable area record and the higher frequencies are recorded in 35 the form of a variable density record which occupies the normally clear part of the variable area record. As will appear, this composite record has the important advantage that it may be played or reproduced by any usual type of push-pull reproducer, such as that disclosed by United 40 States Patent 2,094,737, for example.

The invention will be better understood from the following description when considered in connection with the accompanying drawings, and its 45 scope is indicated by the appended claims.

50 Referring to the drawings,

Figure 1 illustrates the improved type of record,

Figure 2 illustrates the application of the invention to a penumbra type of impulse recorder,

55 Figure 3 illustrates the application of the in-

vention to a combined galvanometer and a light valve recorder, and

Figure 4 illustrates the application of the invention to a multi-galvanometer type of recorder.

Fig. 1 illustrates the positive of a composite photographic record wherein a pair of variable area push-pull record tracks 10 and 11 are separated by a line or narrow opaque band 12, and a pair of variable density push-pull record tracks 13 and 14 are located in the normally clear portions of the record tracks 10 and 11. In this record, the lower frequency components of the recorded impulses are represented by the variable area push-pull track 10—11 and the higher frequency impulses are represented by the variable density push-pull track 13—14. It is, of course, apparent that any suitable means may be provided for separating these different frequency components of the recorded impulses. Since such 20 frequency separating means or filter networks are well known to those skilled in the art, they have not been illustrated in connection with the various illustrated embodiments of the invention.

Fig. 2 illustrates an embodiment of the invention wherein light from a source 15 is projected through a lens 16, a multi-apertured mask 17, a single-apertured mask 18, a cylindrical lens 19 and a spherical lens 20 to a galvanometer mirror 21. From this mirror, light is reflected 25 through a lens 22, the light slit of a mask 23 and a lens 24 to a photographic record 25.

The function of the multi-apertured mask 17 is to produce at the mirror 21 a pair of oppositely shaded penumbra shadows the images of which 30 are vibrated transversely of the light slit 26 in accordance with the high frequency components. Thus the aperture 27 produces at the slit 26 an image 27' which is brightest at its lower edge and becomes gradually darker as its upper edge is approached. Similarly, the aperture 28 produces at the slit 26 an image 28' which is brightest at its upper edge and becomes gradually darker as its lower edge is approached. If the operating coil 29 of the recording galvanometer is energized 40 in accordance with the high frequency impulses, as previously indicated, there is produced on the record strip 25 a high frequency push-pull record track 13—14 such as is shown in Fig. 1.

The low frequency push-pull record track 50 10—11 is produced by the single-apertured mask 18 which is moved longitudinally of the slit 26 by means of operating coils 30 and 31. These coils are supplied with the low frequency components of the recorded impulses, and the distortion 55

otherwise produced by fogging of the valleys and underexposing the peaks of the high frequency waves is not present in such low frequency waves. At the same time, the superiority of the variable area record track with respect to photographic development processes is to a considerable extent retained, i. e., distortion due to operation in the non-linear ranges of the H. and D. curve is largely avoided.

10 It should be understood that the masks 17 and 18 are mounted closely together, only so much separation being provided as is necessary for mechanical reasons, that the function of the cylindrical lens 19 is to sharply focus in the plane 15 of mask 23 the vertical edges of the aperture in mask 18 and of apertures 27 and 28 in mask 17, thus producing images 27'—28' having sharp vertical edges. The apertures 17 and 18 are slightly spaced from one another horizontally 20 for the purpose of separating the images 27' and 28' and producing the image separation line or band 12 of Fig. 1.

Fig. 3 illustrates a modification wherein the variable area low frequency recording is effected 25 by means of a galvanometer and the variable density high frequency recording is effected by means of a light-valve. Thus light is projected from the source 15 through the lens 16, a fixed single-aperture mask 32 and a lens 33 to the recording galvanometer mirror 21. From this 30 mirror, an image 34 of the aperture in the mask 32 is reflected through the lens 22 to the light slit mask 23. By means of the galvanometer 21, this image 34 is vibrated longitudinally of the light 35 slits 35 and 36 of the mask 23 and functions to produce on the record 25 a variable area record similar to the record 10—11 of Fig. 1.

Mounted adjacent to the mask 23 is a three-ribbon light valve 37—38—39 to which the high 40 frequency components of the recorded impulses are supplied through the leads 40 and 41. The use of a three-ribbon light valve in this manner to produce a variable density push-pull sound track is well known. If the opening between the 45 ribbons 37 and 38 is aligned with the light slit 38, and the opening between the ribbons 38 and 39 is aligned with the light slit 35, as illustrated, it necessarily follows that the light transmitted through the slits 35 and 36 is modulated by the 50 impulses applied to the terminals 40 and 41. Thus, when current flows between the terminals 40 and 41 in one direction, the spacing between the ribbons 37 and 38 becomes narrower and that between the ribbons 38 and 39 becomes 55 wider. When the direction of current flow is reversed, the spacing between the ribbons is changed in the opposite manner.

In order that the positive and negative parts 60 of the variable density push-pull records may be recorded directly opposite each other, and thereby suitable for reproduction on a standard push-pull reproducing system, there is provided between the light valve and the record 25 suitable refracting members 42 and 43. These members 65 are so mounted in different angular positions that the portion of push-pull record recorded through the slit 35 is displaced upwardly longitudinally of the record 25, and the portion recorded through the slit 36 is displaced in the 70 opposite direction, thus bringing these two variable density records into the desired 180-degree phase relationship when scanned or reproduced by means of a single line of light. It is, of course, apparent that the use of these refractors 75 may be avoided if the light valve is replaced

by light wedges, in which case the two light slits 35 and 36 may be horizontally aligned with one another.

The modification of Fig. 4 differs from those of the previous figures in that both the high and low frequency recording elements are of the galvanometer type. In this embodiment, light from the source 15 is projected through a lens 44, the single-apertured mask 32 and a lens 45 to the horizontally vibratable mirror of the low frequency variable recording galvanometer 46. Interposed between the mirror of galvanometer 46 and that of the high frequency variable density galvanometer 21 are the lens 16, the multi-apertured penumbra mask 17, the cylindrical lens 19 and the lens 20.

So much of the penumbra mask apertures 27 and 28 as are illuminated by the image 48 of the aperture in mask 32 are imaged at the light slits 46 and 47 in the form of penumbra shadows 20 27' and 28'. As explained in connection with Fig. 1, the vertical edges of the images 27' and 28' are sharply focused by the cylindrical lens 19, and the two images are darkest at their nearest horizontal edges and become gradually brighter as their offset horizontal edges are approached. These images having oppositely graded light intensities, and which move vertically in response to currents supplied to the galvanometer 21, function to produce a variable density push-pull record in exactly the same manner as is now employed and is described in U. S. Patent No. 2,095,318 to G. L. Dimmick.

When the operating coil of the variable area low frequency recording galvanometer is supplied with the low frequency components of the impulses to be recorded, the image 48 which consists in a highly illuminated rectangle, is vibrated by the mirror 46 horizontally with respect to the penumbra apertures 27 and 28 in mask plate 40 17, and the movements of the illuminated area have the same effect on the images 27' and 28' as the horizontal movements of the aperture in the plate 18 of Fig. 1, and there is produced on the record 25 variable area push-pull sound tracks 45 separated by a distance determined by the separation of the slits 46 and 47. When the operating coil of the variable density high frequency recording galvanometer is supplied with the high frequency components of the impulses to be recorded, the penumbra images 27' and 28' are vibrated transversely of the slits 46 and 47 by the mirror 21 and there is produced in the normally clear part of the low frequency variable area record a variable density record of the high 55 frequency components of the recorded impulses.

It would not be feasible to apply to the recording system, as so far disclosed, the usual methods of ground noise reduction because darkening the variable density tracks as is commonly 60 done in present variable density systems and which does not reduce the output of the variable density track would reduce the output from the variable area tracks. It is possible, however, to compensate for the darkening of the track by 65 increasing the amplitude of the light modulation in recording, in the manner described in my U. S. Patent No. 2,064,665. If this expedient is applied to the present invention, the darkening of the variable density track, as for example by 70 biasing the light valve of Fig. 3, would be compensated by increasing the modulation of the low frequency variable area track. Alternatively, ground noise reduction might be obtained by narrowing the relatively transparent area al- 75

otted to the variable density recording, and compensating for the reduced output from the variable density recording, which this narrowing would produce, by increasing the amplitude with which said variabe density track is recorded. The narrowing of the relatively transparent area might be obtained by moving shutter vanes as is now done in making variable width recordings.

It is apparent that the present invention is not restricted to the particular types of recorders herein disclosed, but is readily applicable to various other types of apparatus in view of this disclosure.

I claim as my invention:

15 1. The electrical impulse recording method which includes separating the high and low frequency components of said impulses, recording said low frequency components as a variable area record track, and recording said high frequency 20 components as a variable density record track located in the otherwise transparent part of said variable area sound track.

25 2. The electrical impulse recording method which includes segregating the frequencies of said impulses in different groups, recording one of said frequency groups as a push-pull variable area record track, and recording another of said

frequency groups as a push-pull variable density record track located in the otherwise clear part of said variable area record track.

3. The electrical impulse recording method which includes separating the high and low frequency components of said impulses, recording said low frequency components as a push-pull variable area record track, and recording said high frequency impulses as a variable density record track located in the otherwise transparent 10 part of said variable area record track.

4. A composite electrical impulse record where-on the low frequency components of said impulses are recorded as a push-pull variable area record track, and the high frequency components of 15 said impulses are recorded as a push-pull variable density record track located in the otherwise clear part of said variable area record track.

5. A composite electrical impulse record where-on the low frequency components of said im- 20 pulses are recorded as a variable area record track, and the high frequency components of said impulses are recorded as a variable density record track located in the otherwise clear part of said variable area record track. 25

EDWARD W. KELLOGG.
